UNITED STATES PATENT OFFICE

150,126

DESIGN FOR A RADIO RECEIVER CABINET

Norman Bel Geddes, New York, N. Y., assignor to
Federal Telephone and Radio Corporation, New
York, N. Y., a corporation of Delaware

Application December 6, 1946, Serial No. 135,301

Term of patent 7 years

(Cl. D56—4)

To all whom it may concern:

Be it known that I, Norman Bel Geddes, a citizen of the United States, residing at 50 Rockefeller Plaza, New York, New York, have invented a new, original, and ornamental Design for a Radio Receiver Cabinet, of which the following is a specification, reference being had to the accompanying drawing, forming part thereof.

Fig. 1 is a view in front elevation of the radio receiver cabinet, with the control knobs shown in broken lines;

Fig. 2 is a plan view of the cabinet with the control knobs omitted, and

Fig. 3 is a side view of the cabinet taken from the right-hand side of Fig. 1 with a part broken

away to show the curvature of the dial, the control knobs being shown in broken lines.

The characteristics features of my design reside in the portions shown by means of full lines in the drawing.

I claim:

The ornamental design for a radio receiver cabinet, substantially as shown and described.

NORMAN BEL GEDDES.
